W. St. George Elliott

Inventor,

UNITED STATES PATENT OFFICE.

WILLIAM ST. GEORGE ELLIOTT, OF LONDON, ENGLAND.

KNIFE FOR MOWERS, REAPERS, &c.

SPECIFICATION forming part of Letters Patent No. 394,349, dated December 11, 1888.

Application filed June 22, 1887. Serial No. 242,128. (No model.)

To all whom it may concern:

Be it known that I, WILLIAM ST. GEORGE ELLIOTT, now residing in London, England, have invented certain new and useful Improvements in Knives for Mowers, Reapers, &c.; and I do hereby declare that the following is a full, clear, and exact description thereof, reference being had to the accompanying drawings, and to the letters of reference marked thereon, which form part of this specification.

This invention relates to certain improvements in knives or cutters for mowing-machines and harvesters; and its object is to improve the construction of hollow cutters, the reciprocation of which will keep the cutting-edges of the same constantly sharp. This I accomplish by making the cutters with hard exteriors and soft interiors, in order that the interior part of the cutter will wear away faster than said exterior, thereby causing the cutters to automatically maintain good and effective edges. This object I attain by the means illustrated in the accompanying drawings, in which—

Figure 1 represents a top view of one of the cutters of a harvester constructed according to my invention. Fig. 2 represents a transverse sectional view of the same on line $x x$, Fig. 1. Fig. 3 represents a top view of a modified construction of cutter on line $x x$, Fig. 2. Fig. 4 is a transverse sectional view of the same. Figs. 5 and 6 represent similar views of a third modification.

Referring to the drawings by letter, A indicates the cutter, the cutting-edge of which is of the usual angular configuration, the body consisting of a hollow or concavo-convex shell, as indicated in the drawings. This cutter-shell is made, preferably, of sheet metal bent into the proper shape in any suitable manner; but it may be made of cast metal, if desired. The outer side of the shell is case-hardened, the interior side remaining soft, so that the inner or softer portions of the shell may, by abrasion, wear more rapidly than the outer hardened portion, which forms the cutting-edges of the cutter, thereby keeping the edges sharp and keen.

Instead of constructing the cutters of case-hardened soft metal, as above described, they may be composed of an exterior thin steel

shell re-enforced by an interior shell of soft metal. In some instances the steel shell may be open at the center and replaced by soft metal, as shown in Figs. 5 and 6, the effect of which will also be to preserve the exterior edge of the cutter.

In the drawings the cutters are shown triangular in plan; but it is evident that they may be otherwise shaped without departing from the spirit of my invention, the essential features of which are, as I have said, the hollow exterior hard cutting-edge portion of the cutter and the hollow soft portion on the interior surface of the cutter.

The advantages of my cutter-shell over the ordinary one-quality metal cutters are obvious, in that the latter must be sufficiently heavy or thick to stand the strain incident to usage, and when so made the cutting-edge, being thick, will not wear uniformly, and the exterior portion of the edge will "round up" from wear before the interior has worn sufficiently to keep the exterior of the edge in contact with the guard-finger edges. By my invention the cutters are sufficiently strong, owing to the ductility of the interior portion of the shell, which, however, wears more rapidly than the exterior portion, and the latter portion, the edges of which form the hard cutting-edge, is so thin or narrow that its wear is equal throughout and close contact with the guard-fingers preserved.

Having described my invention, I claim—

As an improved article of manufacture, a cutter for harvesters angular in plan and composed of a concavo-convex shell of metal, the lower or concave portion being composed of softer metal than the outer or convex portion, the whole constructed substantially as described, whereby the edges of the cutters will be kept keen and sharp when the cutters are reciprocated by reason of the unequal wear of the outer and inner portions of the cutter-shell against the guard-fingers.

In testimony that I claim the foregoing as my own I affix my signature in presence of two witnesses.

WILLIAM ST. GEORGE ELLIOTT.
